UNITED STATES PATENT OFFICE.

ZENA ECKELBARGER, OF GOSHEN, INDIANA.

REPRODUCER.

1,311,057.

Specification of Letters Patent. Patented July 22, 1919.

Continuation of application No. 175,205, filed June 16, 1917. This application filed February 4, 1918. Serial No. 215,357.

To all whom it may concern:

Be it known that I, ZENA ECKELBARGER, a citizen of the United States, residing at Goshen, in the county of Elkhart and State 5 of Indiana, have invented new and useful Improvements in Reproducers, of which the following is a specification.

My present invention pertains to reproducers for use in sound-reproducing machines, and is a continuation of my contemporary application filed June 16, 1917, Serial Number 175,205.

The reproducer consists in the peculiar and advantageous construction, novel combinations and adaptation of parts herein-after described and definitely claimed.

In the accompanying drawings, which are hereby made a part hereof:

Figure 1 is a side elevation showing a 20 portion of a tone arm constructed in accordance with my invention.

Fig. 2 is a vertical section of the same.

Fig. 3 is a cross-section, taken in the plane indicated by the line 3—3 of Fig. 1.

25 Fig. 4 is a detail view of the arm section 5. Similar numerals of reference designate corresponding parts in all the views of the drawings.

The tone arm portion 2 that reaches laterally from the usual upright portion is adapted at its forward end 3 to receive a rounded portion or ball 4 on the rear end of the section 5 that is interposed between the portion 2 and the sound box 6.

35 At this point I would have it understood that the sound box 6 *per se* may be of the construction shown or of any other approved type though the specific sound box illustrated, equipped with the stylus construction claimed in my contemporary application filed June 19, 1916, Serial No. 104,433, is well adapted for use in conjunction with my improved tone arm.

In furtherance of my present invention 45 the rear end portion of the section 5 is reduced forming an annular shoulder thereon and its outer end is screw-threaded for the reception of a threaded collar 4^a, thereby forming a circumferential recess between said collar and shoulder, and into said recess is fitted an annular ball 4, a wave spring 5^a, being interposed between the ball and collar to prevent too free movement of the ball around the section 5, and I would 55 have it understood that the said ball and its

complementary socket 3 and spring 5^a constitute important features of the invention.

Formed in the circumference of the section 5 is a groove 7 which extends through about one-fourth of said circumference. The 60 portion 2 is provided at diametrically opposite points with threaded apertures 8 for the engagement of screws 10 which bear loosely in apertures in the ball 4. One screw extends into the groove in section 5 and permits of limited movement of the same and the parts carried thereby so that the reproducer can be readily changed from use on the Edison type of record for use on the Victor type, and vice versa.

By virtue of this construction the sections 2 and 5 are simply, strongly and adjustably connected together, and also in such manner that the sections 5 and 6 are free to move upwardly and downwardly.

70 The connection between the section 5 and the sound box and its appurtenances are clearly illustrated in Fig. 2, and by reference to said figure it will be understood that the depending portion of the section 5 is 80 shouldered at 10^a and exteriorly threaded at 11. The sound box 6 is bored to snugly receive the depending portion of section 5 and to enable the sound box 6 to abut against the shoulder 10^a, and said sound box 85 is also chambered for the reception of a nut 12 which is turned on the threaded end of the section 5. A steel washer 13 is arranged against the inner end of the chamber in the sound box, and an annular wave spring 90 washer 14 is interposed between the nut 12 and said steel washer 13. This construction is calculated to take up lost motion and afford uniform friction, and the steel washer *per se* is adapted to reduce wear. 95 It will also be noted that said construction as a whole renders it feasible to adapt the reproducer to either the hill and vale type of record or the laterally-waving groove type of record.

To limit the movement of the sound box about the depending portion of the section 5, a stop slot 15 is cast in the top of the sound box and a stop pin 16 is carried in the end of the section 5 and so as to move in the 105 said slot 15.

40, 40 are stop lugs on the bottom and one side of the section 5. The said stop lugs serve by bringing up against the end of the section 2 to prevent the reproducer from 110

falling when the tone arm and reproducer are lifted off the record.

Having described my invention, what I claim and desire to secure by Letters Patent, is:

1. In a tone arm, a tubular section, a second tubular section having a circumferential recess formed at its reduced outer threaded end portion, or threaded collar 10 secured to said outer threaded end portion, an annular ball disposed within said recess between the said collar and an annular shoulder formed at the reduced end portion and disposed within the end of the 15 first named section, a spring interposed between the ball and collar to prevent too free movement of the ball, and oppositely disposed screws threaded in the first section and fitted into the apertures of the ball, one

screw extending into an opening formed in 20 the reduced end of the second section.

2. In a tone arm, the combination of a section having an exterior shoulder and a threaded end, a sound box bored to receive said section and arranged to abut against 25 said shoulder and having a chamber, a nut arranged in the chamber of the box and on the threaded portion of the section, and a spring washer disposed within the chamber in contact with the rear face of said nut. 30

In testimony whereof I have hereunto set my hand in presence of two subscribing witnesses.

ZENA ECKELBARGER.

Witnesses:
